UNITED STATES PATENT OFFICE.

JOSEPH F. MERGEN, OF TIPTON, AND GEORGE W. HOOVER, OF OSBORNE, KANSAS.

LUGGAGE-CARRIER.

1,221,559.

Specification of Letters Patent. Patented Apr. 3, 1917.

Application filed September 8, 1914, Serial No. 860,728. Renewed August 30, 1916. Serial No. 117,802.

To all whom it may concern:

Be it known that we, JOSEPH F. MERGEN and GEORGE W. HOOVER, citizens of the United States, residing at Tipton, in the county of Mitchell and State of Kansas, and Osborne, in the county of Osborne and State of Kansas, respectively, have invented certain new and useful Improvements in Luggage-Carriers, of which the following is a specification.

The present invention relates in general to improvements in luggage carriers, and particularly to that type adapted for attachment to vehicles whereby to enable the disposition of suit cases, egg cases and similar articles at a convenient place.

The objects in view are to provide a simple arrangement capable of being cheaply manufactured and which is particularly adapted for adjustment according to the character of the luggage to be carried thereby. The invention possesses numerous advantages among which are its detachability to enable its ready storage in the vehicle when not in use and the fact that it may be readily secured in position on the vehicle without the drilling of holes or otherwise making special provision for its attachment thereto.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a fragmentary view of a vehicle showing the embodiment of our invention attached thereto, as when carrying a box or similar container.

Fig. 2 is an elevation of the invention, Fig. 3 is a top plan view of the same, and, Fig. 4 is a detail fragmentary view in section showing more clearly the details of construction, and taken on the line 3-3 of Fig. 2.

Throughout the following detail description, and on the several figures of the drawings, similar parts are referred to by like reference characters.

Referring to the drawings the invention consists of a pair of side members 1 and 2, each of which consists of an upright portion and a horizontal or base portion, said base portions being arranged side by side and connected together by means of a keeper 3 which is shown as riveted to the base portion of the

member 2 as at 4. The extremity of the base portion of the member 2 is bent downwardly to form a clamping arm 5, the extreme end 6 of which is bent back upon itself in order to afford a substantial thickness for a threaded opening to accommodate a set screw 7. The upper extremity of each of the side members is formed with an eye or opening 8, as most clearly shown in Fig. 1 of the drawings so that a connecting member such as a strap 9 may be passed therethrough to enable the article disposed between the upright portions of the side members to be maintained in position therebetween.

In the actual use of our device we preferably employ a pair of the devices hereinbefore described and each is secured to the motor vehicle through the instrumentality of the clamping arm 5 which is disposed, in a motor vehicle, on the running board 10. The set screws enable the attachment of the carrier at any point of the support and each device may obviously be adjusted with respect to the other at a proper interval to receive an object to be carried and designated in Fig. 1 by the numeral 11. With the object disposed between the side members of each attachment a strap 9 is passed through the openings 8 in the uprights over the top of said object and said strap thereby holds the side members 1 and 2 at a proper adjusted position. Obviously and especially where the object is of a height less than the side members or where it is of a compressible character, this adjustment by the strap is inherent to the tendency of the said side members to bind in the keeper 3 when the strap is tightened. Since the base portions of the side members have free sliding movement, as afforded by the keeper 3 they may be adjusted to accommodate for varying widths of articles by loosening of the strap and which latitude of adjustability is a very essential and advantageous feature of our article of manufacture.

It will be apparent from the foregoing description that the carrier is a very convenient article for tourists or farmers and can be manufactured and marketed at a small expense because of its simplicity of construction.

Having thus described the invention, what we claim as new is:

1. A luggage carrier comprising in combination a pair of corresponding side members each consisting of a metal bar bent laterally at its lower end to provide a base por-

tion disposed in a horizontal plane, the base portions of the said side members being arranged edgewise with respect to one another for relative longitudinal movement, a 5 connection intermediate the said side members including a keeper embracing the base portions of the side members, a fastening securing said keeper to the base portion of one of the side members near the outer end of the 10 latter, said last named side member being extended downwardly and inwardly to provide a spaced clamping arm parallel with the base portion and a set screw mounted on said clamping arm and coöperative with the 15 fastening and in alinement with the connection between the said keeper and one of the side members for coöperation therewith in its clamping action.

2. A luggage carrier attachment consisting of a pair of corresponding flat metal sections, each comprising an upright por-

tion and a horizontal base portion, and said base portions being disposed side by side edgewise to one another, the base portion of one of said side members being formed with 25 a downwardly and inwardly extending clamping arm spaced therefrom, a keeper fastened to the side member having the clamping arm and connecting the base portions of said side members together for free 30 sliding movement with respect to each other, and a set screw carried by the clamping arm and coacting with said keeper to clamp the attachment to a running board or like part.

In testimony whereof we affix our signatures in presence of two witnesses.

JOSEPH F. MERGEN.
GEORGE W. HOOVER.
